PNEUMATIC TUBE TERMINAL

Joseph M. Scanlan, Syracuse, N. Y., assignor, by
mesne assignments, to The Lamson Company,
Syracuse, N. Y., a corporation of Massachusetts

Application March 7, 1934, Serial No. 714,362
Renewed October 28, 1936

17 Claims. (Cl. 243—12)

This invention relates to pneumatic tube systems in which a carrier is propelled through a tube by the pressure of air being made greater at one end of the carrier than at the other. It has particular reference to systems of this character adapted to handle large carriers for the transmission of comparatively large documents or the like. In systems of this sort it has been found that excessive noise and jarring of the apparatus 5 at the delivery ends of the tubes takes place if satisfactory means is not provided for absorbing the energy of the carriers prior to discharge. Accordingly it has been an object of the present invention to provide for the cushioning of the carriers just prior to their discharge from the tubes 10 so as to break the force of their delivery.

More specifically the invention involves the provision of a door at the discharge end of each tube normally retained in closed position by a latch 20 which is automatically released as the carrier approaches the door. Suitable provision is also made for the automatic re-engagement of the latch after the carrier has been discharged and the door returned to its closed position. Also 25 coupled with the latch operating means is provided a connection for assisting in the control of the main control valve by which the carrier impelling flow is regulated. This connection is such as to insure the prompt closing of the control valve 30 when the carrier impelling flow is no longer required.

While certain specific devices will be presently disclosed in detail for accomplishing the foregoing purposes, it will be understood that in its 35 broader aspects the invention encompasses widely different means for accomplishing the same general results. Various objects and advantages of the invention in addition to those already specified will be made apparent from the detailed description of one form of the same which will now be given in conjunction with the accompanying drawings, in which:

Figure 1 is a side elevation of the apparatus associated with the discharge end of a tube forming part of a vacuum system.

Figure 2 is an enlarged view, in side elevation, of the lower end of the tube.

Figure 3 is a front elevation of a portion of the end of the tube, as viewed along the line 3—3 of 50 Figure 2.

Figure 4 is a detail view of a portion of the latch control mechanism as seen along the line 4—4 of Figure 2.

Figure 5 is a side elevation of the detail shown 55 in Figure 4, and

Figure 6 is a vertical section through the main control valve and associated parts.

Referring now to the drawings, in which the invention is shown applied to a suction or vacuum system, a typical transmission tube 10 is indicated in Figure 1. This tube is connected near its discharge end with a suction drum 11 forming part of suitable power equipment. The connections between the tube 10 and the drum include pipes 12 and 13, the latter of which is connected 10 into the lower side of the tube 10 at the point 14. The pipe 13 enters the tube at substantially right angles to its axis at a point near the end, i. e., beyond a bend in the tube which causes the remaining end portion of the latter to incline downwardly at an angle of about 45°. This arrangement is such that as the carrier passes the point 14, its continued movement toward the end of the tube will be insured by gravity, as well as by the momentum of the carrier.

Between the pipes 12 and 13 there is provided a control valve 15 of any suitable construction, preferably of the type adapted to allow a certain minimum flow through the tube when it is not active and arranged to provide for a carrier impelling flow upon the insertion of a carrier into the receiving end of the tube. For this purpose the valve may include a port 16 substantially but not fully closed by a valve 17. To this valve is attached a stem 18, the end of which is arranged 30 to engage a set-screw 19. This screw may be suitably adjusted to maintain the valve 17 a slight distance off of its seat so as to create a desirable minimum flow. A spring 20 may be conveniently provided for urging the valve against its seat and therefore urging the end of the stem 18 against the set-screw 19. This arrangement will provide for a slight flow of air through the tube 10 whenever the power equipment is on. The stem 18 is slidably mounted in a casing 21 divided into two 40 enclosed chambers 22 and 23 by a diaphragm 24. This diaphragm, at its mid-point, is secured to the stem 18. An opening 25 through the outer side of the casing constantly admits air under atmospheric pressure into the chamber 23. At fitting 26 having an open passage through it places the chamber 22 in communication with the pipe 13.

Now, when a carrier is introduced into the tube, the flow of air into the tube is cut off and a slight 50 vacuum is created within the pipe 13. This, by means of the passage through the fitting 26 serves to withdraw air from the chamber 22. The chamber 23 at the opposite side of the diaphragm being in constant communication with the atmosphere, 55

a pressure differential is created on the two sides of the diaphragm and in a very short time this will be sufficient to overcome the spring 20 and cause the valve 17 to be shifted away from its seat 5 into the full open position indicated in Figure 1. A carrier propelling suction or flow is thus produced. The carrier is propelled through the tube by virtue of the atmospheric pressure acting upon its outer end and the sub-atmospheric pressure 10 acting upon its inner end. This condition exists until the carrier passes the point 14, after which it continues to move downwardly under its own momentum and under the force of gravity.

If no means were provided to break the force 15 of the carrier, it would be discharged with such velocity and impact as to jar the apparatus severely and damage not only the equipment but the carriers themselves. The damage resulting in this way is particularly serious in dealing 20 with carriers of the larger sizes. In some installations the carriers may, for example, be 8" x 12" in cross section and, say, 24" long, or even larger. Such carriers when loaded may weigh as 25 much as thirty pounds, or more. The necessity of absorbing the energy of carriers of this size is especially great. Even carriers of smaller size will do considerable damage if not cushioned in some way to lessen the impact in the course of delivery from the tube. The devices illustrated 30 for the purpose of breaking the force of the carriers include a door 27 adapted to close the lower end of the tube 10. This door is held against its seat by means of a latch 28 pivoted upon a bracket 29 secured to the under side of a receiving 35 chute 30. An arm of the latch is connected to a rod 31 slidably mounted in a diaphragm casing 32. Within this casing there is mounted a diaphragm 33 secured to the rod and adapted to shift the latter in the manner to be presently explained. A spring 34 within the diaphragm casing normally urges the diaphragm upwardly and 40 toward the right in Figure 2 and thus urges the rod 31 in the same direction, tending to shift the latch into door-releasing position. On one side 45 of the diaphragm 33 is a chamber 35 maintained constantly at atmospheric pressure by means of an opening through the casing. At the opposite side of the diaphragm is a chamber 36 connected by means of pipes 37 and 38 with the suction drum 11. A valve 39 in this line may be provided 50 to regulate the flow of air through the pipe 38 to the drum. It will be seen that when the system is in operation, the partial vacuum maintained in the chamber 36 through the connections mentioned will cause the diaphragm to swing 55 downwardly under the atmospheric pressure in the chamber 35 and thus compress the spring 34 and, by means of rod 31, rock the latch into door-locking position.

Between the pipe 37 and valve 39 there is provided a T-connection 40 having one branch connected to a vertically extending pipe 41. The upper end of this pipe terminates adjacent the tube 10 and is normally closed by means of a valve 42. This valve is carried by an arm 43 pivotally mounted upon a pin 44 carried by a bracket suitably secured to the tube. As the carrier 45 approaches the door 27, it engages a trip element 46 which extends through the wall of the tube into the path of the carrier. The trip element is secured to a rod 47 rockably mounted in a bracket 48 carried by the tube. Adjacent the end of the rod 47, which extends to the side of the tube, there is provided an arm 49 adapted to 70 engage an arm 50 connected with the arm 43. 75

The arrangement is such that as the trip element 46 is engaged by the carrier and forced outwardly, the arm 49 will engage the arm 50 and cause the valve 42 to be lifted from the end of the pipe 41. This admits air under atmospheric pressure into the pipe and into the chamber 36. Therefore, the pressures on the two sides of the diaphragm 33 are equalized and the spring 34 5 operates to release the latch 28. It will be understood that as the carrier passes downwardly in 10 the tube 10 from the position shown in Figure 1, toward the door, the air entrapped at the lower end of the tube will be compressed and form a cushion tending to retard the carrier and absorb its kinetic energy. However, when the trip element 46 is reached and the latch is released, the pressure of the cushioned air will force the door open and the carrier will be permitted to pass by gravity out of the end of the tube into the chute 30. A pad 51, or other suitable form of buffer, 20 may be provided at the end of the chute to receive the final impact of the carrier.

In order to insure the maintenance of the latch 28 in tripped or released position, until the carrier has been fully discharged and the door returned to its closed position, additional air connections are provided. These include a pipe 52 connected with the pipe 41 through a cross fitting 53. The free end of the pipe 52 is closed by means of a valve 54 carried by an arm 55 pivotally mounted upon a bracket suitably carried by the chute adjacent the door. An arm 56 connected with the arm 55 is arranged to be engaged by an arm 57 secured to a rod or rock shaft 58. This rod supports the door 27 by means of arms 59 secured to the door and also to the rod. By the connections described, it will be apparent that when the door swings open, the rod 58 will be rocked and the valve 54 lifted from its seat. This will admit air into the pipe 52 and pipe 41 so that even after the valve 42 is restored, upon the passage of the carrier beyond the trip element 46, air under atmospheric pressure will be maintained in the chamber 36. This condition will continue so long as the door is partly or fully open. However, upon the discharge of the carrier and the return of the door to its closed position, the ends of the pipes 41 and 52 will be closed and the suction acting through pipes 37 and 38 will create a partial vacuum within the chamber 36 and thus cause the latch to swing into its door-retaining position. Prior to reengagement of the latch, the door will be drawn and held against its seat by the suction within the tube 10. The purpose of the valve 39 will now be made more clear. It must be adjusted to such a position that it will not permit sufficient leakage to overcome the effect of the air entering the tube 41 through the valves 42 and 54. In other words, the leakage of air through the valve must not be so great as to prevent substantially atmospheric pressure being maintained in the chamber 36 whenever either one of the valves 42 and 54 is open. On the other hand, it should be great enough to insure rapid return of the latch to door-holding position after a carrier has been discharged.

Connections are provided for insuring the rapid closing of the main control valve 17 upon the discharge of a carrier. These connections include a pipe 60 joining one side of the cross fitting 53 with the passage through the member 26. Therefore, air under atmospheric pressure will be admitted to the chamber 22 as soon as the valve 42 is lifted. This will permit the spring 20 70 75

to shift the valve 17 to its minimum flow position shown in Figure 6. If desired, the closing of the valve may be further insured by the provision of a vane 61 in the pipe 13. This vane may be attached to a lever pivoted at 62 on the side of the pipe and carrying at its opposite end a valve 63 normally closing a port 64 communicating with the passage through the member 26. The sudden rush of air created upon the discharge of the carrier, as it passes the point 14, impinging upon the vane 61, will rock the lever to lift the valve 63 and admit air directly into the chamber 22. If both of the means described are provided, the closing of the valve promptly upon the discharge of a carrier is doubly insured. One or the other of these means might be eliminated, if desired.

While a specific embodiment of the invention has been described in considerable detail, it will be understood that this is for the purpose of illustration only and is not intended to limit the scope of the invention. Various modifications may be made to suit particular circumstances. The principle of the invention might be employed in connection with a pressure system as well as with the vacuum system illustrated.

What I claim is:

1. In a pneumatic tube system a tube for transmitting a carrier from one point to another, a closure for the delivery end of the tube, means for latching said closure in closed position, means controlled by the carrier as it passes a predetermined point for releasing said latching means, and means for retaining said latching means in released position until the carrier is discharged and the closure restored to closed position.

2. In a pneumatic tube system a tube for transmitting a carrier from one point to another, a closure for the delivery end of the tube, means for latching said closure in closed position, pneumatic means connected with said latching means for operating the same, means controlled by said carrier as it passes a predetermined point for controlling said pneumatic means, and means controlled by said closure for controlling said pneumatic means.

3. In a pneumatic tube system a tube for transmitting a carrier from one point to another, power means connected with said tube, a closure for the delivery end of the tube, a latch for retaining said closure in closed position, pneumatic means for operating said latch, and means in the path of said carrier for controlling said pneumatic means.

5. In a pneumatic tube system a tube for transmitting a carrier from one point to another, power means connected with said tube, a closure for the delivery end of the tube, a latch for retaining said closure in closed position, pneumatic means for operating said latch, means connecting said pneumatic means with said power means to retain the latch in effective position, and means for admitting air to one side of said pneumatic means as the carrier passes a predetermined point to release said latch.

7. In a pneumatic tube system a tube for transmitting a carrier from one point to another, power means connected with said tube, a closure for the delivery end of the tube, a latch for retaining said closure in closed position, pneumatic means for operating said latch, means connecting said pneumatic means with said power means to retain the latch in effective position, means for admitting air to one side of said

pneumatic means as the carrier passes a predetermined point to release said latch, and means for admitting air to said side of the pneumatic means so long as the closure is open.

6. In a pneumatic tube system a tube for transmitting a carrier from one point to another, power means connected with said tube, a closure for the delivery end of the tube, a latch for retaining said closure in closed position, pneumatic means for operating said latch, spring means normally urging said latch into released position, means connecting said pneumatic means with said power means to retain the latch in effective position, and means for admitting air to one side of said pneumatic means as the carrier passes a predetermined point to release said latch.

7. In a pneumatic dispatch system a transmission tube, power means for providing a carrier propelling air flow through said tube, a power control valve, means for automatically opening said valve upon the insertion of a carrier in said tube, a closure for the discharge end of said tube, and means engaged by the carrier as it passes a given point for simultaneously causing the opening of said closure and the closing of said valve by pneumatic means.

8. In a pneumatic dispatch system a transmission tube, power means for providing a carrier propelling air flow through said tube, a power control valve, means for automatically opening said valve upon the insertion of a carrier in said tube, a closure for the discharge end of said tube, a latch for said closure, and means operated as the carrier approaches said closure for controlling the release of said latch and the closing of said valve.

9. In a pneumatic dispatch system a transmission tube, power means for providing a carrier propelling air flow through said tube, a power control valve, pneumatic means for opening said valve upon a drop in pressure in said tube, a closure for the discharge end of said tube, a latch for said closure, a second pneumatic means for controlling said latch, said second pneumatic means being operated by said power means to retain the latch in active position, and means operated as the carrier approaches the closure for admitting air to both of said pneumatic means to close said valve and release the latch.

10. In a pneumatic dispatch system a transmission tube, a closure for the discharge end of said tube, a latch for said closure, pneumatic means for controlling said latch, a pipe arranged to admit air to said pneumatic means for controlling the same, a pair of valves for controlling said admission of air, connections from said closure for operating one of said valves, and means operated by a carrier approaching said closure for controlling the other of said valves.

11. In a pneumatic tube system a tube for transmitting a carrier from one point to another, means for closing the delivery end of the tube to prevent the free escape of air therefrom, means for locking said closing means in closed position, means actuated by the carrier for releasing the locking means after the speed of the carrier has been retarded by compression of air at said delivery end, and means for retaining said locking means in released position until the carrier is discharged and the closure restored to closed position.

12. In a pneumatic tube system a tube for transmitting a carrier from one point to an-

other, a closure arranged to close the delivery end of the tube to provide an air cushion for said carrier, means for latching said closure in closed position, means actuated by the carrier after its speed is retarded by said air cushion for releasing said latching means, and means for retaining said latching means in released position until the carrier is discharged and the closure restored to closed position.

10 13. In a pneumatic tube system a tube for transmitting a carrier from one point to another, power means connected to said tube for providing a carrier propelling flow of air therethrough, a valve for controlling said power means, pneumatic means for operating said valve, a conduit connected directly to said pneumatic means, said pneumatic means being connected to said power means to maintain said valve open while a carrier is passing along the tube, and means engaged 15 by the carrier as it passes a given point in the tube for causing opening of said conduit to the atmosphere thereby promptly closing the valve.

14. In a pneumatic tube system, a tube for transmitting a carrier from one point to another, power means connected to said tube for providing a carrier propelling flow of air therethrough, a valve for controlling the flow of air produced by said power means, means connected to said power means constituting the sole means 20 for holding said valve open by the pneumatic force of said power means, and means actuated by movement of the carrier through the tube at a point near the discharge end of said tube for subjecting said holding means directly to atmospheric pressure to interrupt said pneumatic force acting between said holding means and power means and to close the valve promptly.

15. In a pneumatic tube system, a tube for transmitting a carrier, a source of suction, means

connecting said source to said tube for moving carriers therethrough, a valve in said connecting means, means connected to said suction source for holding said valve open while a carrier is in transit, and means engaged by the carrier near the discharge end of said tube for causing air to be admitted into said holding means to break the suction and close said valve.

16. In a pneumatic tube system a tube for transmitting a carrier from one point to another, power means connected to said tube for providing a carrier propelling flow of air therethrough, a valve for controlling said power means, pneumatic means for operating said valve, said pneumatic means being connected to 10 said power means to maintain said valve open while a carrier is passing along the tube, means actuated by a pneumatic impulse from a moving carrier for causing the closing of said valve, and means engaged by the carrier in the tube for 15 rendering said pneumatic holding means ineffective to ensure closing of said valve.

17. In a pneumatic tube system, a tube for transmitting a carrier from one point to another, power means connected to said tube for providing a carrier propelling flow of air therethrough, a valve for controlling the flow of air produced by said power means, means connected to said power means for holding said valve open by the pneumatic force of said power means, 20 means actuated by a rush of air following a moving carrier for interrupting the pneumatic connection between said holding means and power means to close said valve, and means arranged to be subsequently engaged by said carrier for 25 causing interruption of said pneumatic force to ensure closing of said valve.

JOSEPH M. SCANLAN.
